UNITED STATES PATENT OFFICE.

PIUS KAUL AND CHARLES KAUL, OF LANCASTER, PENNSYLVANIA.

BREECH-LOADING FIRE-ARM.

SPECIFICATION forming part of Letters Patent No. 298,982, dated May 20, 1884.

Application filed February 20, 1884. (No model.)

To all whom it may concern:

Be it known that we, PIUS KAUL and CHARLES KAUL, of Lancaster, in the county of Lancaster and State of Pennsylvania, have 5 invented a new and useful Improvement in Breech-Loading Fire-Arms, of which the following is a full, clear, and exact description, reference being had to the annexed drawings, forming part of this specification.

10 This invention relates to breech-loading fire-arms in which the breech is opened and closed by means of a vertically-sliding block; and the invention consists of the novel construction, hereinafter described and claimed.

15 In the drawings, Figure 1 is a side elevation of part of a fire-arm embodying our invention. Fig. 2 is a longitudinal section of the same showing the breech opened and the hammer cocked. Fig. 3 is a transverse section of the same on line $\alpha\alpha$ of Fig. 1, looking in the direction of the arrow. Fig. 4 is a transverse section on line $\gamma\gamma$ of Fig. 1, also looking in the direction of the arrow; and Fig. 20 5 is an enlarged perspective view of the cartridge-extractor.

25 A indicates the barrel fixed in the bridge or frame B.

CC are the side plates, and DD are the arms, to which the stock is to be secured by 30 means of the screw-bolt D'. The hammer E, pivoted at E' in a suitable support, preferably the forward end of the lower stock-arm, D, is provided with a recess, E², in its rear under side, into which one end of the hammer-spring 35 F is inserted. Below the recess E² the hammer is provided with a projection, E³, having two notches or rests, E⁴, for the sear H² of the trigger H, which is pivoted at H' in the lower arm, D.

40 I is a spring, which gives the trigger a forward tendency, and holds the sear H² in engagement with the notches in the hammer when it is cocked. The hammer-spring F and trigger-spring I are secured by a single screw 45 to the upper surface of the lower stock-arm, D.

I² is a rear projection on the trigger, to limit its movement between the under side of spring I and the upper side of the trigger-guard J.

50 The hammer E, in its under side, is provided with a curved recess, E⁵, with which engages a short arm, G', of the hand-lever G, which lever is pivoted at K in the forward end of the

lower stock-arm, D, below and a little in advance of the hammer-pivot E'. The curve of the recess E⁵ is so formed with respect to the 55 arm G' and the pivot K of the lever carrying said arm that the hammer may be cocked by the arm G' when the latter is thrown forward by the downward or rearward movement of the lever, and when cocked will not be further 60 affected by the movement of the lever. The lever G is also provided with an arm, G³, which extends forward in front of the arm G' and is curved slightly downward, and which engages with the vertically-sliding block L by means 65 of an opening, L², extending through said block from rear to front. The bottom of the opening L² is curved to conform to the shape of the arm G³, which bears on the same in pulling down the block, while the upper wall of 70 the opening is also slightly curved at the front, and is beveled off at the rear to form a shoulder, g, against which the end of the arm G³ rests when the block is raised to its highest position, and whereby said arm is adapted to 75 serve as a brace for securely supporting the block when the breech is closed. With this construction the lever G is adapted to pull down the block L and cock the hammer by a single downward or rearward movement, while 80 its succeeding forward or upward movement again elevates the block to close the breech without disturbing the cocked hammer.

M is the percussion-bolt, supported in an opening, L⁴, in the block L. The bolt is provided with a spiral retracting-spring, M², and a recess, M³, forming transverse shoulders therein, with which shoulders a pin, M', inserted transversely through the block L, engages to limit the movement of said bolt. 85 The action of such a bolt in exploding a cartridge is well known.

The cartridge-extractor O consists of a lever, O', pivoted at O' within a recess in the bridge B, and provided with two arms, O², extending 95 upward in recesses formed in opposite sides of the barrel A, and a third arm, O³, extending rearward and downward through an opening, l, in the block L. The opening l, which is formed at one side of the opening L², extends 100 both higher and lower than the opening L², in order that the bottom and upper wall thereof shall be brought into contact with the arm O², to operate the cartridge-extractor only at the

end of the downward movement of the block L. The cartridge-extractor is returned to its normal position by the contact of the block L with the arms O⁴ in its upward movement.

- 5 When the arm O² is drawn down by action of the block L, the ends of the extractor-arms O⁴ engage the flange of the cartridge and force the shell partly out on top of the block L, from which it may be removed by hand. When the block L is up, the extractor-arms O⁴ lie within recesses A' in opposite sides of the barrel, and the cartridge, when inserted, lies with its flange resting against shoulders a on the inner surfaces of the arms O⁴, by which shoulders the arms are enabled to engage and extract the cartridge.

B' is a lug on the forward part of the bridge B, and B² is a spring-catch attached thereto for engaging the free end of lever G and holding it in position for closing the breech.

L' is a flange to limit the upward movement of block L.

What we claim is—

1. The combination of the hand-lever G, having the arms G' G³, the sliding block L, having an opening, L², receiving arm G³, and the hammer E, having the curved recess E³, receiving arm G' and being engaged thereby, substantially as shown and described, where-

30 by the lever is adapted to pull down the said block and cock the hammer simultaneously, and then to return the block and leave the hammer cocked.

2. The combination of the lever G, having arm G³, and the sliding block L, having the 35 opening L², provided with a curved bottom, against which said arm G³ may be made to bear to pull down the block, and a shoulder, g, at its top, against which the end of arm G³ may be made to bear to hold the block in a 40 raised position, substantially as shown and described.

3. The combination of the vertically-sliding block L, having the vertical longitudinal openings L² and l, the opening l being of greater 45 vertical extent than the opening L², the lever G, having the arm G³ placed in the opening L², and the cartridge-extractor having the arm O² placed in the opening l, whereby the block may be drawn down and the cartridge-ex- 50 tractor may be operated only at the end of the downward movement of the block, substantially as specified.

PIUS KAUL.
